US0D1068744S

(12) **United States Design Patent** (10) **Patent No.:** **US D1,068,744 S**
(45) **Date of Patent:** **** Apr. 1, 2025**

(54) **MICROPHONE**

(71) Applicant: **Topping Technology Co., Ltd.**
Guangzhou (CN)

(72) Inventor: **Hailin Huang**, Guangzhou (CN)

(**) Term: **15 Years**

(21) Appl. No.: **29/916,298**

(22) Filed: **Nov. 9, 2023**

(51) LOC (15) Cl. **14-01**

(52) U.S. Cl.

USPC **D14/228**

(58) **Field of Classification Search**

Primary Examiner — Paula Allen Greene

(57) **CLAIM**

The ornamental design for a microphone, as shown and described.

DESCRIPTION

FIG. 1 is a front, top perspective view of a microphone, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the microphone that form no part of the claimed design.

1 Claim, 8 Drawing Sheets
